DESIGN FOR PANTIES

Helen Lee, New York, N. Y., assignor to Leo J. Goldberger, New York, N. Y.

Application January 27, 1936, Serial No. 60,816

Term of patent 3½ years

To all whom it may concern:

Be it known that I, Helen Lee, a citizen of the United States, residing at New York city, in the county and State of New York, have invented a new, original, and ornamental Design for Panties, of which the following is a specification, reference being had to the accompanying drawing forming a part thereof.

Fig. 2 is a rear elevational view thereof drawn on a reduced scale.

I claim:

The ornamental design for panties as shown. In testimony whereof I have signed this specification.

HELEN LEE.
